ACOUSTICAL TILE

Merritt W. Seymour, Jr., Leola, Pa., assignor to Armstrong Cork Company, Lancaster, Pa., a corporation of Pennsylvania

Filed Nov. 14, 1963, Ser. No. 77,438

Term of patent 14 years

(Cl. D18—2)

Fig. 1

I claim:

The ornamental design for an acoustical tile, substantially as shown.
